UNITED STATES PATENT OFFICE

2,441,382

BACKPLATE LATCH FOR MACHINE GUNS

Louis A. Anderson, Dayton, Ohio, assignor to
General Motors Corporation, Dayton, Ohio, a
corporation of Delaware

Application May 25, 1945, Serial No. 595,671

9 Claims. (Cl. 89—199)

1

This invention relates to ordnance and more particularly to an improved back plate latch for machine guns.

It is an object of this invention to provide an improved safety means for preventing accidental operation of the latch which holds the back plate of the machine gun in place.

A further object of this invention is to simplify the latch mechanism.

Another object of this invention is to provide a safety means which may be changed over from right-hand operation to left-hand operation with a minimum amount of effort and inconvenience.

A further object of this invention is to reduce the cost of the latch mechanism.

A still further object of this invention is to provide a latch mechanism which includes a safety device which is unaffected by the jarring action resulting from the firing of the gun.

Further objects and advantages of the present invention will be apparent from the following description, reference being had to the accompanying drawings, wherein a preferred form of the present invention is clearly shown.

In the drawings:

Fig. 1 is a fragmentary plan view of the breech end of a machine gun;

Fig. 2 is a side view, with parts broken away, of an end plate showing the relationship of the safety mechanism to the latch element;

Fig. 3 is a rear view, with parts broken away, showing the manner in which the safety plunger is supported within the end plate;

Fig. 4 is a side elevational view of the safety plunger; and

Fig. 5 is a horizontal sectional view showing the construction of the plunger.

Referring now to the drawing wherein there is shown a machine gun of the Browning type comprising a receiver 10 which includes a bottom plate 12 and a top plate 14. The breech end of the machine gun is provided with vertically disposed grooves 16 for receiving opposite tongues 18 provided on the back plate 20 which is assembled by a downward movement and supported by the bottom plate 12 in accordance with standard practice. The back plate 20 carries a buffer 22 which absorbs the energy of recoil of the breech bolt. A latch 24 is mounted within a slot 26 provided in the lower end of the back plate 20 and is supported therein by means of a pin 28 arranged as shown in Fig. 2. The nose 30 of the latch 24 is arranged to engage under the rear end of the bottom plate 12 as indicated in Fig. 2.

2

and is normally held in latching engagement by means of the coil spring 32.

In order to eliminate difficulties which have been encountered with the present latch mechanism, I have provided a simplified safety means for preventing accidental or unintentional operation of the latch. My improved safety means comprises a slidable bar element or plunger 40 which is arranged to be slidably supported within a transversely extending passage 42 provided directly in the back plate 20. As indicated in Fig. 2, the bottom portion of the back plate is made thicker than the upper portion of the back plate in order to accommodate the plunger 40. The plunger 40 is limited in its movement by the removable pin 44 which passes through the slots 46 provided in the upper and lower walls of the plunger 40, as shown. The one end of the plunger 40 is hollowed out as indicated in Figs. 3, 4 and 5 so as to accommodate a coil spring 48 which serves the dual purpose of biasing the plunger 40 into safety position and to hold the stop pin 44 in assembled relationship. It will be observed that the stop pin 44 is provided with circumferential grooves 50 which cooperate with the outer convolution of the coil spring 48 in such a manner that the pin 44 is prevented from dropping out.

The back plate is provided with two holes 52 and 53, either one of which may be used for accommodating the pin 44 whereby the plunger may be mounted for operation from either side. As explained hereinabove, the pin 44 is held in place by means of the coil spring 48 with the result that the pin 44 may be removed by compressing the spring 48. Upon removal of the pin 44 from the hole 52, for example, the plunger 40 together with the spring 48 may be removed and inserted from the opposite end of the passage 42 and the pin 44 may be reassembled in the hole 53. The spring 48 may be compressed by inserting any convenient tool, such as a screw driver, in through the open end of the cavity within which the spring 48 is mounted.

As best shown in Figs. 2, 3 and 4, the plunger 40 is provided with a cut away portion 41 with the result that when the cut away portion 41 is lined up with the upper side of the latch 24, the latch 24 may be operated so as to cause the nose 30 to clear the bottom plate 12. But, when the round portion of the plunger 40 is disposed above the latch 24, as shown in Fig. 3, it is impossible to release the latch 24. The sides of the plunger 40 are relieved or cut away at points 43 so as to provide clearance between the plunger and the

By virtue of the above described arrangement, it is apparent that any jarring of the gun during firing will have no tendency to cause the safety plunger 40 to move out of safety position, whereas with the prior art safety provided on the present .50 caliber machine gun, the reciprocating movement of the gun during recoil tends to cause the safety to bounce out of safety position. It is also apparent that the plunger 40 is very conveniently located for engagement by the operator's thumb as the operator grips the buffer 22 in the palm of the hand and operates the latch 24 with one of his other fingers.

While the form of embodiment of the invention as herein disclosed constitutes a preferred form, it is to be understood that other forms might be adopted, as may come within the scope of the claims which follow.

What is claimed is as follows:

1. In a machine gun, a back plate of the type adapted to be slidably mounted in the receiver of a gun by a lowering movement, a latch pivotally carried adjacent the lower portion of said back plate and arranged to engage the receiver to hold the back plate in place, spring means biasing said latch into latching position, a slideable safety element carried by said back plate for locking said latch in latching position, said back plate having a transverse aperture within which said safety element is slidably mounted, said safety element comprising a plunger having a hollow portion, a spring disposed within said hollow portion, a pin carried by said back plate arranged in engagement with said last named spring, said pin having groove means formed thereon in alignment with the convolutions of said spring for engagement by said spring.

2. In combination, a support, a latch carried by said support, a safety for said latch comprising a plunger slidably mounted by said support and having a portion movable into and out of locking engagement with said latch, a recess within said plunger, a coil spring within said recess, and a stop pin carried by said support and passing transversely through said plunger and said recess, said pin having groove means formed thereon in engagement with the convolutions of said spring, said spring serving to hold said pin against movement.

3. In a machine gun, a back plate of the type adapted to be slidably mounted in the receiver of a gun by a lowering movement, a latch pivotally carried adjacent the lower portion of said back plate and arranged to engage the receiver to hold the back plate in place, spring means biasing said latch into latching position, said back plate including an integral portion having a transverse aperture therein adjacent said latch, said back plate having a cutaway portion transversely intersecting said aperture providing clearance space sufficient to permit the unlatching movement of said latch, a pin constituting a plunger slidably mounted within said transverse aperture, and spring means acting upon said plunger pin for biasing said pin to project a portion of said plunger pin into said clearance space to prevent the unlatching of said latch.

4. In a machine gun, a back plate of the type adapted to be slidably mounted in the receiver of a gun by a lowering movement, a latch pivotally carried adjacent the lower portion of said back plate and arranged to engage the receiver to hold the back plate in place, spring means biasing said latch into latching position, said back plate including an integral portion having a trans-

verse aperture therein adjacent said latch, said back plate having a cutaway portion transversely intersecting said aperture providing clearance space sufficient to permit the unlatching movement of said latch, a pin constituting a plunger slidably mounted within said transverse aperture, and spring means acting upon said plunger pin for biasing said pin to project a portion of said plunger pin into said clearance space to prevent the unlatching of said latch, a stop means within said aperture stopping said pin when it projects a predetermined distance into said clearance space, a portion of one end of the plunger pin protruding from said aperture to serve as an operating means to move the plunger pin out of the position in which it prevents unlatching.

5. In combination, a support, a latch carried by said support, said support having first and second passages arranged at right angles to one another, a slotted plunger operable in said first passage and having a portion movable into and out of locking engagement with said latch, a stop pin passing through said slotted plunger and arranged in said second passage, and spring means having one end pushing against said plunger and having the other end pushing against the side of said pin, said pin having notched means within which the end of said spring rests so as to releasably hold the pin in place.

6. In combination, a support, a latch carried by said support, a hollow plunger slidably mounted in said support and having a portion movable into and out of locking engagement with said latch, a coil spring disposed within the hollow of said plunger, a slot in one wall of said plunger, and a pin carried by said support and projecting through said slot and serving to limit the movement of said plunger, said pin having a circumferential groove arranged in engagement with said spring whereby said spring holds said pin in place, the end of said spring being accessible from one end of said hollow plunger whereby said spring may be compressed so as to disengage said pin.

7. In a machine gun, a back plate of the type adapted to be slidably mounted in the receiver of a gun by a lowering movement, a latch pivotally carried adjacent the lower portion of said back plate and arranged to engage the receiver to hold the back plate in place, means biasing said latch into latching position, said back plate having an integral portion projecting rearwardly therefrom and provided with a transversely extending aperture, a slideable safety element supported within said aperture with one end normally projecting from said recess at one side of said integral projecting portion, said safety element having a first portion which when lined up with said latch allows operation of the latch and having a second portion movable into alignment with said latch to lock said latch in latching position, said safety element having a spring receiving recess formed therein, a spring within said recess, a removable pin having at least one end engaged within a recess formed in said integral projecting portion, said pin forming an abutment for said spring and also cooperating with said safety element to limit the movement thereof, said pin having a shoulder cooperating with said spring so as to removably hold said pin in place.

8. In a machine gun, a back plate of the type adapted to be slidably mounted in the receiver of a gun by a lowering movement, a latch piv-

totally carried adjacent the lower portion of said back plate and arranged to engage the receiver to hold the back plate in place, means biasing said latch into latching position, said back plate having an integral portion projecting rearwardly therefrom and provided with a transversely extending aperture, a slidable safety element supported within said aperture with one end normally projecting from said recess at one side of said integral projecting portion, said safety element having a first portion which when lined up with said latch allows operation of the latch and having a second portion movable into alignment with said latch to lock said latch in latching position, said safety element having a spring receiving recess formed therein, a spring within said recess, a removable pin having at least one end engaged within a recess formed in said integral projecting portion, said pin forming an abutment for said spring and also cooperating with said safety element to limit the movement thereof, said pin having a shoulder cooperating with said spring so as to removably hold said pin in place, said spring receiving recess having an opening through which said spring is accessible for moving the spring out of engagement with said pin whereby said pin may be removed.

9. In a machine gun, a back plate of the type adapted to be slidably mounted in the receiver of a gun by a lowering movement, a latch pivotally carried adjacent the lower portion of said back plate and arranged to engage the receiver to hold the back plate in place, means biasing said latch into latching position, said back plate having an integral portion projecting rearwardly therefrom and provided with a transversely ex-

tending aperture, a slidable safety element supported within said aperture with one end normally projecting from said recess at one side of said integral projecting portion, said safety element having a first portion which when lined up with said latch allows operation of the latch and having a second portion movable into alignment with said latch to lock said latch in latching position, said safety element having a spring receiving recess formed therein, a spring within said recess, said slidable safety element being adapted to be inserted into said aperture from either side so as to be operable from either side, a pin for limiting movement of said element, said integral projecting portion having a pair of holes for selectively receiving said pin on either side of said latch, said pin having a shoulder cooperating with said spring so as to be removably held in place whereby said pin may be removed from one of said holes and said slidable safety element turned end for end and reassembled and held in place by the use of the same pin while located in a different hole.
